United States Patent

Des. 240,229
Patented June 8, 1976

240,229

BATHTUB ENCLOSURE DOOR

George F. Mendenhall, 510 W. Hickory St.,
Hinsdale, Ill. 60521

Filed July 15, 1974, Ser. No. 488,713

Term of patent 14 years

Int. Cl. D23—02

U.S. Cl. D23—69

FIG.2

FIG.3

FIG. 1 is a front elevational view of a bathtub enclosure door showing my new design;

FIG. 2 is a top plan view thereof; and

FIG. 3 is a side elevational view thereof.

The characteristic feature of my design resides in the specific ornamentation thereon.

I claim:

The ornamental design for a bathtub enclosure door, as shown and described.
